UNITED STATES PATENT OFFICE.

EPPA H. RYON, OF PASADENA, CALIFORNIA, ASSIGNOR TO CROMPTON & KNOWLES LOOM WORKS, OF WORCESTER, MASSACHUSETTS, A CORPORATION OF MASSACHUSETTS.

TUBE-FRAME SUPPORT.

Application filed October 20, 1923. Serial No. 669,868.

To all whom it may concern:

Be it known that I, EPPA H. RYON, a citizen of the United States, residing at Pasadena, in the county of Los Angeles and State 5 of California, have invented a new and useful Tube-Frame Support, of which the following is a specification.

This invention relates to means for supporting a yarn tube frame in an Axminster carpet or other similar loom. These tube 10 frames provide bearings for the yarn spools and support the numerous yarn tubes through which the pile yarn is presented between the warps of the carpet or other fabric. 15

It is the general object of my present invention to provide improved devices for supporting a yarn spool on the tube frame and for attaching the tube frame to the transporting pattern chain. 20

Particular features of my invention relate to improvements in the construction of the chain engaging hook and to improved means for assembling the support or bracket with 25 the tube frame.

My invention further relates to arrangements and combinations of parts which will be hereinafter described and more particularly pointed out in the appended claims. 30

A preferred form of the invention is shown in the drawings in which—

Fig. 1 is a partial front elevation of a tube frame, partly in section and showing my improvements applied thereto; 35

Fig. 2 is an end elevation of certain parts shown in Fig. 1, and

Fig. 3 is an enlarged detail view to be described.

Referring to the drawings, I have shown 40 a portion of a tube frame 10 of rectangular tubular structure and supporting a large number of yarn tubes 11 through which yarn is delivered from a yarn spool 12. The end bracket or support for the tube frame is shown as formed in two parts 13 and 14, these parts being preferably permanently secured together by welding or in some other convenient manner. 45

The part 13 provides a bearing for one 50 end of the yarn spool 12 and the part 14 engages the usual transporting chain (not shown). The part 13 is provided with a laterally projecting portion or arm 15 which extends within the tubular member 10 and is

secured thereto by screws 16. The bracket 55 member or part 14 extends transversely across the end of the tubular member 10 and a projecting end portion 17 of the member 10 is bent upwardly to engage the end of the part 14 and is secured thereto by screws 60 18. The tube frame bracket or support is thus very firmly secured to the end of the tubular member 10 and accidental displacement thereof is effectively prevented.

A chain engaging hook 20 is formed with 65 a curved bearing portion 21 and an offset spring-engaging portion 22. The entire hook is preferably formed from a single rigid piece of material and is secured in the member 10 by a cross pin 23 extending across 70 the tubular member and preferably riveted at its ends therein.

The outer or swinging end of the hook 20 extends upward through slots in the bracket 75 member or part 14, as clearly indicated in Fig. 1. A spring 24 is inserted between the lower wall of the member 10 and the under side of the inner portion 22 of the hook 20. This spring 24 holds the hook 20 yieldingly 80 in the position shown in Fig. 1. For convenience in assembling, the spring 24 is preferably secured to the end portion 22 by a stud 25 (Fig. 3). When thus constructed, the hook and spring may be assembled before the parts are inserted in the tubular 85 member 10 and thereafter constitute a single unit.

Having thus described my invention, it will be seen that the parts are conveniently manufactured and readily assembled and 90 that a strong, substantial and reliable structure results from the use of my invention. It will be further evident that changes and modifications can be made therein by those skilled in the art within the spirit and scope 95 of my invention as set forth in the claims and accordingly I do not wish to be otherwise limited to the details herein disclosed, but—

What I claim is:—

1. In a loom, a tubular member, a supporting bracket comprising a spool-bearing portion having an arm extended at right angles thereto and detachably secured within said tubular member and having a chain-engaging portion fixed to said spool-supporting portion, extending transversely across the end of said tubular member, and abut- 100
105

ting the ends of the side walls thereof, and said tubular member having an end portion bent around the lower end of said chain-engaging portion of said bracket to engage the outer face thereof, and means to detachably secure said parts together.

2. In a loom, a tubular member, a supporting bracket secured thereto, a rigid hook extending freely through an opening on said 10 bracket and having a pivotal bearing portion, and a bearing stud for said hook fixed in the walls of said tubular member.

3. In a loom, a tubular member, a supporting bracket attached thereto, a rigid hook 15 extending freely through an opening in said bracket and supported independently of said bracket, said hook having a pivotal bearing portion within said tubular member and

having an offset end projection, means fixed in said tubular member to pivotally support 20 said hook, and a spring permanently secured to said end projection and engaging an inner wall of said tubular member to hold said hook yieldingly in operative position.

4. As an article of manufacture, a rigid 25 chain-engaging hook adapted for use in a hollow tube frame having an open end, said hook having a curved portion forming an open bearing and having a laterally projecting end portion, a coil spring to move said hook, and means to permanently secure said spring to the projecting end portion of said hook to be handled as a unit therewith.

In testimony whereof I have hereunto affixed my signature.

EPPA H. RYON.
